UNITED STATES PATENT OFFICE.

ARTHUR OGDEN HUBBARD, OF SAUK CENTRE, MINNESOTA.

ADJUSTABLE RECLINING-CHAIR.

SPECIFICATION forming part of Letters Patent No. 336,115, dated February 16, 1886.

Application filed March 30, 1885. Serial No. 160,598. (No model.)

To all whom it may concern:

Be it known that I, ARTHUR OGDEN HUBBARD, a citizen of the United States, and a resident of Sauk Centre, county of Stearns, 5 and State of Minnesota, have invented certain new and useful Improvements in Adjustable Reclining-Chairs, of which the following specification is a full, clear, and exact description, reference being also had to the accompanying 10 drawings, in which—

Figure 1 is a side elevation, Fig. 2 is a front elevation, and Fig. 3 is a rear elevation, of one of the chairs complete. Fig. 4 is a detached perspective view of the foot-rest. Fig. 15 5 is a detail in section of a portion of the arm-rest, &c. Figs. 6 and 7 are enlarged detached details of the brake mechanism. Figs. 8, 9, and 10 are details illustrating the construction 20 of the seat portion of the chair. Figs. 11 and 12 are enlarged perspective views of the seat-brace clamping-joint.

A' A² are two bars forming the sides of the back-section, B' B² two similar bars forming the sides of the seat-section, and C' C² two 25 similar bars forming the sides of the foot-section, the lower ends of the back-bars A' A² being united by hinges a' to the rear ends of the seat-bars B' B², while the upper ends of the foot-bars C' C² are united by hinges a² to 30 the forward ends of the seat-bars B' B². The hinges a' are detachable, so that the back-bars may be disconnected from the seat-bars when 35 the chair is to be folded up, as hereinafter explained.

Any suitable form of hinge may be used; but in practice I have found that simple screw-eyes answer the purpose admirably. The back-bars A' A² and the foot-bars C' C² are perforated, as shown, to receive lacing-cords 40 b, by which the canvas or other textile body or web D may be secured to the bars, as shown. The outer edges of the bars A' A² and C' C² are grooved, as shown at d in Fig. 1, the 45 grooves connecting the outer ends of perforations, so that the lacing-cords b will be embedded in the bars, and not only out of sight, except from the sides, but protected from wear by the over-projecting wood of the bars. The lacing is held in the grooves, as it reaches 50 from one perforation to another, by being drawn taut in the perforations. At its ends the web D will be turned over and sewed

down, leaving hems, in which the end bars, A³ and C³, will be inserted. These end bars are held in the ends of the bars A' A² and C' C² by tenons on their ends fitting into mortises in the ends of the bars, as shown. The lacings b, by being drawn tight, will thus hold the side bars in place with reference to the web, while the hems on the web will hold the 60 end bars in place in the bars. The lacings also permit the web to be easily and quickly tightened in event of its becoming loosened, or the replacing of a worn or torn web. The webs may be of any suitable material—65 canvas, carpet, or other material—or a combination of two or more materials. The seat-section is re-enforced underneath by an extra web, E, (see Fig. 8, 9, and 10.) which is formed of a tube of canvas having circular 70 bars F' F² in its interior, by which it may be secured to the inner edges of the seat-bars B' B² by screws or nails e. The web D lies over this auxiliary web E loosely, and completely hides it, the function of the latter being to 75 give additional support to the web D, where the greatest strains occur. On the inner lower edges, at the centers of the bars B' B², metal sockets G' G² are secured, each supporting one end of a brace, H' H², each of the latter being 80 provided on its other end with a clamping-plate, K' K², the adjacent surfaces of the latter being provided with radiating interlocking notches h, (see Figs. 11 and 12,) and adapted to be clamped together by a bolt, i. 85 It will be readily understood, therefore, that by loosening the bolt i until the plates K' K² are disconnected, the bars H' H² may be pushed upward by their lower ends, and spread the bars B' B² apart, and hold them thus by again 90 tightening up the bolt i. By this means the bars B' B² are not only held apart and prevented from being drawn toward each other by the pressure upon the webs D and E, but the latter may be retightened in event of sagging. 95

M' M² are the arm-rests, which are connected at their rear ends by brackets to the back-bars A' A², near their lower ends, while the forward ends of the arm-rests are connected by 100 similar brackets to the foot-bars C' C², as shown. These brackets consist of small metal bars N', pivoted by their ends in the ends of the arm-rests, and also in slots cut into the

back-bars $A' A^2$ and the foot-bars $C' C^2$, as shown, and each of the bars N' is provided with angular braces N^2 , connecting them with their respective bars $A' A^2$ and $C' C^2$. The brackets $N' N^2$ are each of them rigid, so far as their connections with the back and foot sections are concerned, and have the arm-rests pivoted loosely in their outer ends. Attached to the under side of each arm-rest is a "chock" or stop, P' , whose functions are to check and regulate the throw of the chair, as hereinafter shown.

The three sections above described, and covered with the web D , are arranged to be mounted upon and supported by a folding base or frame, as shown. This frame consists of two legs, $R' R^2$, pivoted at n' to the seat-bars $B' B^2$, near their forward ends, and having two other shorter legs, $R^3 R^4$, pivoted at r to the legs $R' R^2$, the legs $R' R^2$ being also connected together by a round, R^5 , and the legs $R^3 R^4$ being similarly connected by a round, R^6 , while a chain or chains, R^7 , are arranged to connect the rounds, to prevent the legs spreading too far apart, while at the same time adapted to allow the frame to be folded up, as hereinafter shown.

$R^8 R^9$ are two arms rigidly fixed by opposite bracing-bars, $t' t^2$, which connect their lower ends to the legs $R' R^2$, while their upper ends are pivoted at n to the back-bars $A' A^2$, near their lower ends, as shown. By this means the jointed back, seat, and foot sections are poised upon the frame, and may be bent upward into a chair shape with the back and foot sections at right angles to the seat-section; or the back-section may be turned down to nearly a horizontal position, which, by reason of its having the arm-rests pivoted thereto, will cause the foot-section to be thrown upward to a correspondingly horizontal position, and thus transform the chair into a couch. Of course the chair may be placed in any intermediate position which may be desired. The "chocks" or "stops" P' are so arranged that, when the chair is bent up into the form of an ordinary chair, the lower ends of the chocks will strike the seat-section and arrest the further forward movement, and prevent the back-section folding over upon the other parts or upon the occupant of the chair. The chocks also perform the same office when the chair is transformed into a couch, by striking the seat-section at the other end of the stroke and preventing the back section from sinking too low. Beneath each of the chocks P' curved guides P^2 are attached to the seat-sections, and provided with channels in their upper faces, in which the lower ends of the chocks run, to prevent the clothing of the occupants of the chair from catching beneath the chocks.

T' is a rod passing through the arms $R^8 R^9$, and provided on one end with a head, v' , and on the other with a cam hand-wheel, T^2 .

T^3 is a bar pivoted by one end at v^3 to the side bar, B' , and having a slot, v^4 , in its other end, through which the rod T' passes.

T^4 is a small cam-disk, having lugs on its rear face by which it fits over the bar T^3 , and is prevented from turning thereon, and having clutch-teeth v^5 on its outer face corresponding to similar teeth, v^6 , on the cam-hand-wheel T^2 . The rod T' passes through the slot in the bar T^3 , and also through the cam-disk T^4 , and is rigidly fixed in the hand-wheel T^2 . By this simple device a brake is formed by which the bar T^3 may be clamped to the arms $R^8 R^9$, and thus hold the chair at whatever inclination the occupant may desire. The length of the rod T' will be graduated to correspond with the distance between the arms $R^8 R^9$, so that when the straight sides of the teeth $v^5 v^6$ are in contact the bar T^3 will be loose and free to be moved by the adjustment of the chair; but when it is desired to lock the chair in any desired position, then it is only necessary for the occupant to turn the hand-wheel T^2 , which will cause the clutch-teeth to move the hand-wheel away from the cam-disk and compress the bar T^3 firmly between the arm R^8 and the cam-disk. A foot-rest is arranged upon the chair, consisting of a main bar or foot-rest, w' , and two small side bars, $w^2 w^3$, the latter provided with small pegs $w^4 w^5$, which are adapted to rest above and below the foot-bars $C' C^2$ when the rest is inserted into its place, as shown in Figs. 1 and 2. The pegs w^4 thus hold the rear end of the foot-rest and prevent its being pushed out by the foot of the operator. Additional pegs, x , will be inserted into the lower sides of the bars $C' C^2$, above which the pegs w^4 may be placed when it is desired to adjust the rest to suit younger or shorter occupants of the chair.

The connections between the supporting-frame and the chair or seat portion will be so arranged that they may be disconnected to enable the chair to be folded up for transportation. Nearly all the other parts are also adapted to be disconnected, so that the chair may be folded up into a small space for convenience of transportation.

Having described my invention and set forth its merits, what I claim is—

1. The seat-section, back-section, and foot-section hinged together and having the web D , attached thereto by lacings b , and provided with brackets $N' N^2$ and arm-rests $M' M^2$, connecting said brackets, in combination with a folding supporting-frame consisting of legs $R' R^2$, pivoted to said seat-section, bracing-legs $R^3 R^4$, flexible connections R^7 , and arms $R^8 R^9$, attached by one end to said legs $R' R^2$, and pivoted to said back-section by their other ends, substantially as and for the purpose set forth.

2. In a reclining-chair, the back-section, foot-section, and seat-section hinged together, and having the web D , attached thereto by lacings b , said seat-section having re-enforcing web E , substantially as set forth.

3. In a reclining-chair, the back-section, foot-section, and seat-section hinged together, and having the web attached thereto by lacings b , said seat-section having sockets $G' G^2$,

bracing-arms H' H², fitting into said sockets, and provided with clamping-plates K' K², substantially as and for the purpose set forth.

4. The seat-section, back-section, and foot-section hinged together, and having the web attached thereto by lacings, and provided with brackets N' N² and arm-rests M' M², connecting said brackets, in combination with a folding supporting-frame consisting of legs R' R², pivoted to said seat-section, bracing-legs R³ R⁴, flexible connections R⁵, and arms R⁶ R⁷, attached by one end to said legs R' R², and pivoted to said back-section by their other ends, and a brake consisting of rod T', having cam-
15 wheel T², slotted arm T³, and cam-plate T⁴, substantially as set forth.

5. A back-section, a seat-section, and a foot-section hinged together, and having the web attached thereto by lacings b, and provided with brackets N' N², arm-rests M' M², connecting said brackets, and provided with stops P', and grooved guides P², attached to said seat-section, substantially as and for the purpose set forth. 20

In testimony whereof I have hereunto set 25 my hand in presence of two subscribing witnesses.
